WALTER R. ROYCROFT, OF OZONE PARK, NEW YORK, ASSIGNOR TO COLUMBIA PHONOGRAPH COMPANY, INC., OF BRIDGEPORT, CONNECTICUT, A CORPORATION OF NEW YORK

RECORD CENTERING MEANS FOR MULTIPLAYING MACHINES

Application filed March 30, 1929. Serial No. 351,190.

This invention relates to phonographs or talking machines and has particular relation to automatic or multiplaying phonographs.

An object of the invention is to provide a centering means for centering disc records.

A further object of the invention is to provide a means adapted to receive a plurality of phonograph records of various diameters, and to center the records one at a time, before they are passed to the turn table.

An additional object of the invention is to provide a record centering means adapted to have a number of ten and twelve inch, or other diameter records, placed therein without regard to their order or relation of centers, and which will center each record as it becomes the bottom record of the stack.

Yet another object of the invention is to provide a record centering means having the characters stated and including means for receiving each record as it is centered and positioning it ready to be transferred to a turn table.

A still further object of the invention is to provide a record centering means including a record lowering platform adapted normally to support the weight of a stack of records, and adapted to be intermittently lowered and raised, to deliver the bottom record of the stack to means for transferring it to a turn table.

An additional object is to provide a record centering means adapted to receive a stack of records and including fingers adapted to engage each of said records as it becomes the bottom record of the stack, and center it on a vertically movable platform which normally supports the weight of the records off the centering means, and which is adapted to descend with the centered record and deliver it to means for transferring it to a turn table.

Yet another object of the invention is to provide a record centering means including a hopper-like receptacle adapted to receive a plurality of records of different diameter, in combination with record centering fingers adapted to separate the bottom record from the stack and centralize it with relation to the receptacle.

Other and additional objects and advantages will become more apparent from a consideration of the following detailed description, taken in connection with the accompanying drawings. This description and the accompanying drawings deal with one specific embodiment of the invention, and since various changes in construction, combination and arrangement of parts will readily suggest themselves, to those skilled in the art, reference must be had to the annexed claims for a definition of the limitations of the invention, since many changes and modifications may be made without departing from the spirit of the invention as claimed.

In the drawings:—

Fig. 1 is a top plan view of my improved record centering means;

Fig. 2 is a side elevational view of the same; Fig. 3 is a top plan view of the receptacle and centering means removed from the operating means;

Fig. 4 is a bottom plan view of the part shown in Fig. 3;

Fig. 5 is a sectional view on the line 5—5 of Fig. 1;

Fig. 6 is a sectional view on the line 6—6 of Fig. 3;

Fig. 7 is a detailed perspective view of one of the finger centering means; and

Fig. 8 is a structural detail.

Figures 9 and 10 are plan and side elevational views, respectively, of the operating mechanism shown in dotted lines in Figures 1 and 2.

Referring in detail to the drawings, the invention is shown as mounted on a motor board or other support 10. Disposed on the upper side of the motor board is the record receptacle or stack holder indicated in its entirety at 11, and comprising a top annulus 12 carrying a plurality of space guide blocks 13, four being shown. Receptacle 11 is provided with a skirt portion 14 extending substantially two-thirds of the way around it, and contacting with the support 10, and being secured thereto by means of screws, bolts or the like passing through lugs formed with the skirt portion. The inner surface of the space guide blocks 13 inclines downwardly and in-

wardly and stop at the inner edge of the annulus 12.

Disposed below the annulus 12 is a ring 16, Fig. 4. This ring is of less diameter than the diameter of the annulus 12 and the ring is guided by rollers 15 and supported by spaced slide blocks 17, four such slide blocks and four such rollers being shown. Disposed one on each of the guide blocks 17 and pivotally connected at their rear ends to the ring 16, are four separating and centering fingers 18. These fingers are pivotally mounted on pins 19 and are pivoted to the ring 16 as by means of pins 20. Pins 19 are partly embedded in the record guide pieces 13 as clearly shown in Fig. 6.

Fingers 18 have two normal positions; one is extended in full line position as shown in Figs. 3 and 4 and the other position is within the pockets 21, as clearly indicated in Figs. 1, 3 and 4. The fingers are moved to their respective positions through movement of the ring 16. Obviously, owing to the pivoted arrangement of the fingers, movement of the ring 16 in one direction will move the fingers into the pockets 21 and movement of the ring in the opposite direction will again swing the fingers out of the pockets.

At times, the entire weight of the records in the receptacle 11 is supported by the fingers 18. However, normally, the weight of the record is on a vertically movable plate on platform 22 (Fig. 5) arranged in the center line of the receptacle 11 and carried by a bracket 23 (Fig. 2) secured to the upper end of a post 23a vertically slideable in bearings 24 on the frame piece 25. This frame piece is disposed below the support 10.

Also supported at the under side of the plate or support 10 is the frame 26. Supported by the frame 26 is a cam shaft 27 carrying a gear 28 driven by a gear 29a through the medium of a gear 29', (Fig. 2) secured to a power shaft 30 driven in any suitable manner. Cam shaft 27 carries and drives cam 31 having a cam groove 32 in which is disposed a roller 33 carried by and arranged intermediate the ends of an arm 34. This arm 34 at its inner end is pivotally secured to a projection 35 of the frame 26, as at 36. A vertically arranged lever 37 is pivoted to a frame intermediate its ends to the frame, as at 38, and at its upper end engages a pin or stud 39 carried on the lower side of the ring 16. Movement of the lever 37 on its pivot 38 obviously will result in movement of the ring 16. At its lower end, lever 37 carries a stud 40 which is embraced by the bifurcated end 41 of the arm 34 (Fig. 8). From the foregoing, it will be seen that oscillating movement imparted to the arm 34 by the cam 31 will be transmitted through lever 37 to ring 16 resulting in the opening and closing of the fingers 18.

Also disposed on cam shaft 27 is a cam 42 which engages and rocks an arm 43 pivoted as

at 44. The forward end of arm 43 is bifurcated (see Fig. 2) and engages a pin 44a carried by the post 23. Since vertical locking movement is imparted to the arm 43 by the cam 42, this movement will be transmitted from the arm to the post 23 resulting in raising and lowering of the plate at the proper times.

A third cam 45 is carried on the shaft 27 and this cam raises and lowers a pin 46 having an extension 46a. This extension is a movable member, and moves with a plate 46b. When plate 46b is to be removed, the extension 46a which passes through the records that have been played or rejected is removed with the plate. In other words 46 and 46a comprise in general a split pin arrangement. 46 and 46a do not move upward until a record is delivered back to the magazine from the turn table, when 46a passes through the usual center hole in the record and holds the record while it is released from the carrying means. When the record is released it drops to its position on plate 46b. When platform 22 delivers a record from the magazine to the carrier, it strikes 46a causing 46a and 46 to fall to their normal positions, provision having been made in the cam 45 to permit this.

A detail of the fingers 18 is given in Fig. 7, and it is to be noted that these fingers include a knife-edge portion 50 which inclines at a graduated taper from the forward end to the surface 54 so as to form a blunt back as shown. At their forward ends, the fingers are cut away as at 51 to provide a shoulder 52.

When a record is disposed on the fingers in engagement with the four shoulders 52 the record is centered with respect to the receptacle 11 and the notches 51 are, in the present instance, so arranged as to accommodate a record 10 inches in diameter. If a record is 12 inches in diameter, it will ride up the inclined surfaces 53 of the fingers, passing over the notched portion 51 and coming into a position where it engages the shoulders 54 of the fingers. These shoulders are so spaced as to accommodate a 12 inch record.

In the operation of the magazine device a stack of mixed 10 inch and 12 inch records are placed in the receptacle, and they are supported on the plate 22. The fingers are in the pockets 21 and the top of the plate 22 is in a horizontal line with the lower surface of fingers 18. As the mechanism operates fingers 18 they pass under the surface of the lower record of the stack, centralizing the lower record. Now the fingers are withdrawn and the plate or table 22 lowered a distance to bring the bottom record just below the lower surface of the fingers. Here the plate pauses and the cam 31 acts to move the ring to project the fingers, and as the fingers move out of their pockets, the knife-edge passes under the second record from the

bottom lifting the stack off of the bottom record and centering the then bottom record on the fingers.

The plate then descends to the position shown in Fig. 5 carrying a record 55 (the lower record of the stack). Means (not shown, which form the subject matter of another invention) take hold of the record and the table 22 lowers allowing the record to be carried to the turntable without the surface of the record sliding on the table 22. The record is carried to the turntable through the opening under that part of the annulus 12 from which the skirt 14 does not project. After the record is moved from the table 22, the table pausing until after the record is clear of the table, the table then is moved upward under the stack of records, bearing the stack of records, while the fingers 18 recede into the pockets. The stack of records is then supported by the table. Table 22 remains in this position and the first record is returned to the position where it was above table 22. The pin 46a is then projected upward through the hole in the record, holding the record while it is being released from the carrier mechanism. After being released from the carrier mechanism, the record descends to plate 46b which is located on bracket or frame 26 (Fig. 2). Table 22 then descends with the next record, pushing the pin 46a downward into its normal position.

To remove the records, the plate with the records delivered from the turntable is slid across surface of bracket 26 carrying the records and pin 46a. The records are then taken off the plate over the pin 46a, and the plate with the pin replaced in its normal position.

The graduated taper of the fingers 18, when the fingers are in operation, separates the record below from the record being centralized, also when a 12 inch record is above a 10 inch record that is being centralized, separates the above record from the record being centralized. It is obvious that if a 10 inch record were off center one inch, with a 12 inch record above it, in the centralizing of the 10 inch record, there would be a rubbing action between the upper surface of the 10 inch record and the lower surface of the 12 inch record, due to the fact that the inner edge of the annulus at the lower portion of the spaced guide blocks 13 is not great enough in diameter to allow the above centralization. Therefore, the fingers raise the 12 inch record to eliminate this condition.

Having thus described the invention, what is claimed is:-

1. In a record centering means, in combination, a receptacle adapted to receive a stack of records of various diameters, and movable means adapted to be projected beyond the walls of said receptacle to engage and center the lowermost record of said stack

irrespective of the diameter of said lowermost record.

2. In a record centering means, in combination, a receptacle adapted to receive a stack of records of various diameters, and retractable fingers adapted to be projected beyond the walls of said receptacle for engaging and centering the lowermost record of said stack irrespective of the diameter of said lowermost record. 75

3. In a record centering means, in combination, a receptacle adapted to receive a plurality of records of various diameters, and means within the receptacle for separating the bottom record from the stack and for supporting the stack, said means acting to center the lowermost record of the stack irrespective of the diameter of said lowermost record. 80

4. In a record centering means, in combination, a receptacle adapted to receive a record, movable fingers adapted to engage and center said record in the receptacle, and said fingers having notches whereby they are adapted to engage and center records of various diameters. 85

5. In a record centering means, in combination, a receptacle adapted to receive a record stack, means movable through one open end of said receptacle to support said stack, and means within said receptacle to separate one record from the stack and support the stack and leave said record on the means movable through one end of the receptacle. 90

6. In a record centering means, a receptacle having an open end, a plate movable through said end to engage the lowermost record of the stack and to support the stack, and means within said receptacle for cutting the stack away from the lowermost record and supporting the stack free of the lowermost record. 100

7. In a record centering and supporting means, a receptacle adapted to receive a stack of records, a plate movable through the lower end of said receptacle to engage and support the stack of records, and means within the receptacle adapted to elevate the stack away from the lower record and to center the then lower record of the stack. 105

8. In a record centering and feeding mechanism, a receptacle adapted to receive a record, a plate movable in said receptacle and adapted to support said record, pivoted fingers in said receptacle adapted to be moved to center the record, means to move said fingers, said means comprising a ring having a pivotal connection with each of the fingers, a cam to oscillate the ring, a support for said plate, and means to raise and lower said support. 115

9. The combination as in claim 3, said separating means comprising fingers having inclined portions. 120

10. The combination as in claim 3, said separating means comprising fingers having cut- 125

away portions whereby the fingers have portions inclined transversely from a knife-edge.

11. The combination as in claim 3, said separating means comprising fingers having cut-away portions whereby the fingers have portions transversely inclined and longitudinally tapered.

12. In a record centering means, in combination, a receptacle adapted to receive a plurality of records, means within the receptacle for separating the bottom record from the stack and for supporting the stack, said means comprising inclined tapered fingers having spaced notches for centering records of various diameters.

Signed at New York, in the county of New York, and State of New York, this 26th day of March, A. D. 1929.
